UNITED STATES PATENT OFFICE.

STELMER D. RICH, OF NEWPORT, MAINE, ASSIGNOR OF ONE-HALF TO CUYLER W. RICH, OF NEWPORT, MAINE.

HOT-AIR HEATER.

Application filed June 21, 1928. Serial No. 287,278.

The invention relates to heaters wherein air from a suitable source is circulated through the furnace and utilized both for heating and ventilating.

5 In accordance with the invention a heater or furnace is provided having an air space around the ash pit, air passages in the walls of the fire box, banks of flues at the sides of the combustion chamber and extending there-
10 over at an upward inclination, and damper controlled air inlets for admitting air into the air space surrounding the ash pit.

While the drawing illustrates a preferred embodiment of the invention, it is to be understood that in adapting the means to meet specific needs and requirements, the design may be varied and such other changes in the minor details of the invention as claimed may be made without departing from the spirit 20 thereof.

For a full understanding of the invention and the merits thereof, reference is to be had to the following description and the drawings hereto attached, in which:-

25 Figure 1 is a vertical sectional view of a furnace embodying the invention on the line 1-1 of Figure 2 looking in the direction of the arrows.

Figure 2 is a vertical transverse sectional view on the line 2-2 of Figure 1 looking to the left as designated by the arrows.

Figure 3 is a horizontal sectional view on the line 3-3 of Figure 1.

Figure 4 is a horizontal sectional view on the line 4-4 of Figure 1.

Figure 5 is a detail sectional view on the line 5-5 of Figure 4.

Corresponding and like parts are referred to in the following description and designated in the several views of the drawings by like reference characters.

The invention is applicable to furnaces and heaters of various types and designs. The heater illustrated embodies an ash pit 1, a fire box 2 and a combustion chamber 3. An air space 4 surrounds the bottom and three sides of the ash pit, a pipe 5 connects with the bottom of the furnace and supplies fresh air to the space 4.

50 The upper portion of the pipe 5 flares as indicated most clearly in Figures 1 and 2 of

the drawings. Openings 6 are formed in the bottom of the heater and extend beyond the upper flared portion of the pipe 5. A circular plate 7 is pivotally mounted upon the top of the bottom of the heater and is provided with an inner set of openings 8 and an outer set of openings 9, the latter being exterior to the upper flared portion of the pipe 5 as indicated most clearly in Figure 5 of the drawings. This plate constitutes a damper and is operable by means of a handle 10 which projects through and below the bottom of the heater. The openings 8 and 9 are disaligned, or alternate, thereby admitting of adjustment 55 of the damper to admit air into the space 4 from the pipe 5 or from the space exterior to the pipe, or from both the pipe and the surrounding space as may be desired.

As indicated most clearly in Figures 1, 2 and 3 of the drawings banks of flues are provided at the back and opposite sides of the combustion chamber and are in communication with the space 4 surrounding the ash pit 1. The fire box preferably consists of a casting in which vertical openings 11 are formed and with which the respective flues connect. The flues 12 at one side of the combustion chamber extend vertically thence laterally across the combustion chamber at an 60 upward inclination as indicated at 13.

The flues 14 at the opposite side of the combustion chamber are similarly formed and extend across the combustion chamber at an upward inclination as indicated at 15. The 65 inclined portions 13 and 15 cross one another at an intermediate point as indicated most clearly in Figure 1 of the drawings. The flues 16 at the rear of the combustion chamber 70 3 comprises vertical portions and upwardly inclined portions 17 the latter extending over the inclined ends 13 and 15 of the side flues. The several flues connect with the openings 11 of the fire box by means of a slip joint.

By having provision for the admission of 95 fresh air and by having the air passages 11 in the walls of the fire box the latter is prevented from warping and burning out so quickly and the air passing through the air passages 11 is heated and is further heated 100 in its passage through the several groups of flues 12, 14 and 16 and put into circulation.

In this manner the dwelling or other place not only may be more effectively heated but may be ventilated by a supply of fresh, pure heated air.

5 Having thus described the invention, I claim:—

A hot air furnace having an air space surrounding the ash pit, and having inner and outer openings in its bottom, a pipe connected 10 with the bottom of the furnace and adapted to

supply fresh air to the said air space through the inner openings formed therein, and a plate pivoted upon the bottom of the furnace and formed with inner and outer openings to alternately, or partly register with the said inner and outer openings formed in the bottom of the furnace.

15 In testimony whereof I affix my signature.

STELMER D. RICH. [L. s.]
